UNITED STATES PATENT OFFICE.

JULIUS LICHTENSTEIN, OF GÖTTINGEN, GERMANY.

CLOCK AND WATCH.

No. 878,076.

Specification of Letters Patent.

Patented Feb. 4, 1908.

Application filed July 8, 1907. Serial No. 382,753.

To all whom it may concern:

Be it known that I, JULIUS LICHTENSTEIN, a subject of the German Emperor, and resident of Göttingen, Germany, have invented 5 new and useful Improvements in Clocks and Watches, of which the following is a specification.

Hitherto safety-devices for clock springs have become known in which upon the spring 10 being sufficiently wound up the winding-up member is brought out of gear with the parts to be wound up, and that after a certain number of turns of the clock spring bolt.

The present invention provides also such a 15 safety contrivance, by which moreover the key is by means of a separate spring thrown off from the clock spring bolt, so that the clock spring is prevented from being further wound up. For this purpose, the clock 20 spring bolt is provided with the separate spring mentioned, which is freed by the wound-up spring of the clock releasing an arresting device, and which is thus adapted to throw the key off from the winding-up 25 bolt. The arresting device consists of a pin or a pawl which catches into a notch of a sleeve which is arranged between the separate spring and the key, and which pawl carries a rod which can be turned aside by 30 means of a projection provided on the clock spring so that the pawl leaves the notch in the sleeve and allows thus the separate spring to come in action.

The accompanying drawing shows the new 35 safety contrivance.

Figures 1 & 2 show the same in a diagrammatical sectional elevation and plan respectively, with the clock spring in unwound position, while Figs. 3 & 4 are similar views to 40 the former, with the clock spring in wound-up position ready to throw off the key; Fig. 5 shows a modification of a single part of the device.

On the disk *a* a square bolt *b* is fixed on 45 which a spiral spring *d* is disposed and connected at its upper part with a square shell *e* and at its lower part with a square shell *f*. The latter is provided with a slot through which the clock spring *g* is passed and fixed 50 with one end to the bolt *b* and with the other end to the outside of the disk *a*. The upper shell *e* is provided with a notch *e*¹. The pin *h* which is movably fixed on the disk *a*, has a

projection *i* and carries a lateral rod *k*. The clock spring *g* is provided with a projection *l*. 55 The key *m* is made to fit the bolt *b*.

The operation of the safety contrivance is as follows:—In the position of the parts shown in Figs. 1 & 2, the clock spring is unwound. If now, for the purpose of winding up the 60 spring, the key *m* is put on the bolt *b* one presses down the sleeve *e* and compresses thereby the spiral spring *d* until the projection *i* of the pin or pawl *h* catches into the notch *e*¹ of the shell *e*. The winding-up of 65 the clock spring is now effected until the rod *k* abuts against the projection *l* of the clock spring which gradually alters its position, whereby the rod *k* is shifted aside thus turning the pin *h* so that the projection *i* leaves 70 the notch *e*¹. The separate spring *d* now being untensioned, lifts the shell *e* thereby throwing the key off from the bolt *b*. The arrangement may be also made in such a manner that the upper shell *e* has, instead of 75 a notch, a projection *e*² against which strikes the projection *i* of the pin *h* (see Fig. 5).

Having fully described my invention, what I claim and desire to secure by Letters Patent is—

A safety contrivance for the springs of 80 clocks and watches, comprising in combination with the clock spring, its winding-up bolt, and base disk; a lower sleeve (*f*) arranged in said clock spring, and an upper sleeve (*e*) arranged above said clock spring 85 on said bolt and provided with a notch (*e*¹), a separate spiral spring arranged on said bolt between said sleeves, a key (*m*) designed to fit said bolt, a movable pin (*h*, *i*) designed to 90 catch into the notch in said upper sleeve, a lateral rod (*k*) projecting from said pin, and a projection (*l*) provided on said clock spring 95 and adapted to engage said rod and thus to cause said pin to leave said notch in said upper sleeve upon the clock spring being sufficiently wound up, for the purpose set forth.

In testimony whereof I have hereunto set my hand in the presence of two subscribing 100 witnesses.

JULIUS LICHTENSTEIN.
